ROLLING MILL

Frank J. Wood, New Rochelle, N. Y., assignor to
Erwin Loewy, New York, N. Y.

Application April 23, 1947, Serial No. 743,345

2 Claims. (Cl. 80—55)

1

This invention relates to rolling mills, and particularly to an improved arrangement therefor whereby the rolls and bearings may be removed, assembled, and adjusted as units with greater ease than hitherto possible.

In rolling mill operation, various adjustments are required necessitating that the mill rolls be axially and vertically adjustable relative to each other. In addition, the rolls frequently must be changed for various reasons such as in merchant mill practice wherein a multiplicity of various shapes are rolled requiring different shape rolls, or where repairs to the rolls are needed.

In prior practice, the roll bearings, and other parts therefor have been insertable and removable from the rolling mill stand individually so that many parts had to be handled and adjusted, thus making roll changing or adjusting operations time consuming and difficult. A rolling mill stand normally has roll housings at each end thereof, each of said roll housings being composed of a pair of uprights defining a window serving as a receptacle for support for the roll bearings. Each time the rolls have been removed for any purpose, a substantially complete readjustment of the rolls and bearings relative to each other and to the mill housings normally has been required.

One of the objects of the present invention is to simplify the manner and reduce the time in which a roll assembly can be removed, changed, and adjusted in a rolling mill, so as to reduce materially the loss in productive operation of the mill due to the removal, changing, and adjusting of the rolls. The rolling mill can not be productively used during the period while the mill is stopped when the rolls are being changed or when the parts are being adjusted in the roll stand.

Another object of the invention is to make possible the adjustment of the roll and bearings as a unit before being placed in the mill.

Still another object of the invention is to simplify and to reduce materially the number of parts necessary to make the roll adjustments and the number of adjustments required.

One of the features of the invention is the provision of a roll assembly carrier frame in which a roll and roll bearing arrangement can be assembled outside of the rolling mill and the roll assembly carrier frame with the roll and bearings assembled therewith inserted and removed as a simple unit in the mill housing.

Another feature of the invention is that the uprights composing the roll housings can be tied

2

together at their tops by bridges without interfering with the insertion and removal of the roll assemblies. Such a construction of the mill housings provides a strong and rigid structure.

5 In accordance with this invention, roll assembly carrier frames are provided which can be passed horizontally through the two windows or apertures normally present in the two uprights at either side of the roll mill housing. In each roll carrier frame, the roll bearings can be mounted and properly adjusted relative to the carrier frame and to a roll supported by said bearings before the carrier frame with the roll and roll bearings assembled thereto is inserted as a unit through and in the windows of the roll housing. The roll assembly carrier frame can be clamped to one pair of uprights or housing of the rolling mill stand after the carrier has been inserted therein and is located in its desired vertical position relative to the rolling mill housings. The lower roll carrier frame can be clamped or fastened in some suitable manner to the housing uprights or may be adjustably positioned relative to the housings in various ways. Thus, the roll and bearings may be adjusted relative to the roll assembly carrier frames before being put into position in the housings, thereby saving the assembly and adjustment of a plurality of parts in the mill stand. Also, the adjustments and assembly of the roll and bearings to a carrier frame can be made while the rolling mill is still operating with another set of rolls, bearings, and carrier frames, thereby saving valuable machine time.

35 One or both of the carrier frames can be made so as to be adjustable lengthwise relative to the mill housings, and/or the rolls can be adjusted lengthwise relative to the carrier frames. The pressure of the bearings longitudinally against the roll necks can be adjusted by providing suitable means on each roll carrier frame for this purpose, this adjustment being made, if desired, before the carrier assembly is placed in the rolling mill housings.

40 45 In a two-piece roll bearing arrangement, the term "chock" is used herein to mean the bearing half against which pressure is exerted when material is being rolled; in other words, the upper halves of the bearings for the upper roll and the lower halves of the bearings for the lower roll. The term "roll guide bearing" is used herein in conjunction with two-part bearings to designate the bearing half opposite the roll chocks. In a "two-high" mill these are the upper and lower bearing halves adjacent and back-to-back near

50

55

the mating line of the rolls. The roll guide bearings are sometimes referred to in the art as the roll carrier bearings.

Where the usual two-piece bearing arrangement is used, the upper roll guide bearing halves may be mounted on spring upwardly urged elevating rods or steelyards. In this manner, the upper guide bearing halves will exert upward pressure on the upper roll so that the upper roll necks will be held against the upper roll chocks. The spring urged elevating rods for the upper roll can have an arrangement whereby the rods may be positively lowered so that the upper roll assembly can be lowered away from the upper screw-down apparatus and thereby permit easy removal of the upper roll assembly. An hydraulically operated toggle link arrangement can be used for lowering the spring elevating rods although, of course, other equivalent means to lower the rods can be employed. When toggle links are employed, the rods may be positively held in their retracted position by merely causing the toggles to move past a dead center position.

Still another feature of the invention is a quickly retractable locking means to hold the lower carrier frame in its lowermost operating position in the housing after it has been assembled thereto.

Another feature which can be alternately used with a two-piece roll bearing is a spring separated roll guide bearing assembly wherein the upper and lower guide bearing halves are joined by bolts or rods which loosely connect the same, there being springs between the halves to keep each pair of upper and lower guide bearings separated relative to each other. This arrangement can be used in place of elevating rods and will cause the rolls to engage their respective roll chocks.

In place of two-piece bearings, roller bearings may be employed in conjunction with the present invention and assembled in the roll carrier frames.

The invention is shown in conjunction with a simple "two-high" rolling mill, but it is evident that it may be applied to various types of mills, such as ones having more than two rolls.

These and other objects, features, and advantages of the invention will become apparent from the following description and drawings which are merely exemplary.

Fig. 1 is an elevation partly in section.

Fig. 2 is an end view of Fig. 1 looking from the right end of Fig. 1, portions of the frame being broken and some parts being shown in section.

Fig. 3 is a sectional view taken along the line 3—3 of Fig. 1.

Fig. 4 is a sectional view taken along the line 4—4 of Fig. 1, a portion of the frame being broken away so as to show the details of the toggle arrangement.

Fig. 5 is an elevation partly in section of a modification of the form shown in Fig. 1.

Fig. 6 is an end view of the form shown in Fig. 5 looking from the right end, some of the frame being broken away and parts shown in section.

Fig. 7 is a sectional view taken along the line 7—7 of Fig. 5.

Fig. 8 is a sectional view taken along the line 8—8 of Fig. 5.

Fig. 9 is a fragmentary end view of a modified form of support for the carrier bearings of Figs. 5 and 6.

Fig. 10 is a fragmentary elevation, partially in section, of the form shown in Fig. 9.

Fig. 11 is a fragmentary elevation showing the invention applied to roller bearings.

In the embodiment of the invention shown in Figs. 1 to 4, inclusive, rolls with two-piece bearings are used, each bearing including a chock and a mating roll guide bearing. The upper roll 10 therein has roll chocks 11 and 12 rotatably guiding the uppermost portion of the roll neck bearings at each end of the roll, the chocks having suitable anti-friction metal linings 13. The linings may have thrust collars 14 and 15 integral with the lining or separate therefrom, said thrust collars being located between the inner margins of the roll chocks and the shoulder formed at the junction of the reduced roll neck and the roll itself. The upper roll guide bearings 16 and 17 can have anti-friction metal liners 18. Guide bearings 16 and 17 are connected to the roll chocks 11 and 12 loosely by means of bolts or rods 19 extending between each of the flanges 16a of the guide bearings and the corresponding flanges of the roll chocks. The loose connection of said bolts with the guide bearing halves and the chocks will allow vertical movement of the roll guide bearing relative to its mating roll chock. The manner in which the upper roll bearing guides are urged upwardly will be described in detail hereafter.

The upper roll chocks 11 and 12 are mounted in the roll carrier frame, yoke, or cradle 20. The flanges 21a at one end of roll carrier frame 20 extend beyond the end wall 21 of the carrier frame and the margins of window 22 (Fig. 2) of the roll housing 23. The window or aperture 22 is formed between uprights 24 and 25 of the roll housing 23 (Fig. 2), and there is a similar window between uprights 24b and 25b of the left-hand roll housing (Fig. 1). When the roll carrier frame is located in an assembled position in the roll housings, said flanges 21a will engage uprights 24 and 25 on seats 24a and 25a thereof. Liners 90 may be placed along the inner edge of uprights 24 and 25 and the spacing between the liners made such that the roll carrier frame is tightly held sideways in the window 22. The other end of the roll carrier frame 20 is similarly positioned between uprights 24b and 25b in the left roll housing. Keeper plates 26 engage flanges 21a and are removably held in place by means of bolts 27. It is evident that various types of securing means can be employed for keeping the carrier frame in an assembled position in the roll housings and that various arrangements of the uprights defining the windows or equivalent supporting apertures or guide surfaces for the roll supporting means can be used.

The upper roll chock 12 is held in place in the roll carrier frame by means of bolts 29 (Figs. 1 and 3) which may be adjustable, if desired, and upper roll chock 11 is positioned longitudinally or axially in the roll carrier frame 20 by means of adjustable bolts 28, the adjustment of said bolts in the carrier determining the pressure exerted by the roll chocks on the thrust bearings 14 and 15 which engage the roll, thus assisting in positioning the roll longitudinally in the carrier frame and governing the pressure of the roll chocks and their thrust bearings longitudinally on the roll.

The position of the top roll 10 relative to the lower roll and the mill housing can be adjusted by means of housing screws or screw-downs 30 and 31, said housing screws being adjustable vertically by means of worm wheels 32 and 33 which are turned by shafts 34 and 35, respectively. Pads at the ends of the housing screws 30 and 31 engage the top surface of the carrier frame 20. The shafts 34 and 35 may be driven by hand, motor,

or in any desired manner. Indicators 36 may be placed on each shaft so as to cooperate with suitable dials to show the position of each of the housing screws 30 and 31.

The uprights 24 and 25 have a bridge 37 joining the tops thereof, and there is a similar bridge for uprights 24b and 25b, thus providing a solid and rigid frame, which will not interfere with the easy placement of the assembled carrier frames in the roll housings.

Lower roll 38 has a pair of roll chocks 39 and 40 which are adjustably mounted in the lower roll carrier frame 41. Roll chock 40 can be assembled to the roll carrier frame 41 by bolts 47. Lower roll chock 39 is adjustably positioned in the carrier frame 41 by means of adjustable bolts 42, said adjusting bolts serving to determine the longitudinal pressure exerted by the roll chock thrust bearings 39a and 40a on the shoulders of the roll.

The lower roll carrier frame 41 has a depending lug 44 with a slot therein for straddling the double flanged collar 45, said collar being adjustable longitudinally on stud 43 relative to the mill housing by means of nuts 46. The longitudinal or axial position of roll carrier frame 41 relative to the roll housings and the upper roll thus can be varied by axial adjustment of flanged collar 45. In this manner, the axial positions of rolls 10 and 38 relative to each other can be adjusted with ease, the rolls and pressure of the thrust bearings thereon having previously been adjusted relative to each carrier.

Lower roll guide bearings 48 are held in place against the necks 38a of the lower roll 38 by means of springs 49 carried on bolts 50, said bolts being fastened into the roll chocks and passing loosely through apertures 50a in the lower roll guide bearing flanges.

The lower roll carrier frame 41 can be releasably retained in its operating or down position by one or more locking pins 51 (Figs. 2 to 4) mounted on the uprights of the housing. The locking pins 51 have tapered ends 52 engageable with similarly shaped elongated slots in the lower roll carrier frame 41. The slots must be elongated to allow for horizontal adjustment of the roll carrier frame. Locking pins 51 can have operating collars 53 at one end thereof. Springs 54 surround locking pins 53 and are retained in apertures 91 by means of removable keeper plates 56. Springs 54 are arranged so that one end of each abuts the collars 55, said collars being secured to the shafts of pins 51. The springs thus tend to normally hold the locking pins 51 in a locking position relative to the lower carrier frame.

In order to retract the locking pins so that the carrier can be raised upwardly or moved horizontally, a yoke 57 can be provided for each pin, said yoke being oscillatable by shaft 58, the shaft being rotatable in any suitable manner. A motion limiting arm 59 is mounted on shaft 58 and is cooperative with pin 60 mounted on the mill housing frame so as to limit movement of yoke 57 when shaft 58 is rotated. The locking pins can be omitted, if desired, and especially so if other arrangements are provided for positively holding the lower carrier frame from vertical movement.

The upper roll guide bearings 16 and 17 are positioned vertically by rods or "steelyards" 63, said rods normally being held in elevated positions by springs 61 acting on collars 62, said collars being secured to rods 63. Four rods 63 are provided, one for each upright 24, 25, 24b, and 25b so that there will be a rod engageable

with each flange of the guide bearing halves. In the position shown in Fig. 2, the upper roll guide bearings 16 and 17 and the upper roll 10 are urged upwardly by springs 61 acting through rods 63 so that the upper roll is held in its uppermost position and with the roll necks thereof in roll chocks 11 and 12.

In order to permit a lowering of the upper roll assembly, the lower ends of rods 63 can be fastened to a crosshead 64 by means of nuts 65. Crosshead 64 is vertically movable by means of an hydraulic cylinder 67 or similar operating apparatus, the hydraulic cylinder 67 being pivotally mounted at 68 on brackets 69 depending from the main frame of the machine. Piston rod 70 is fastened to a link operating connector 71, said connector having side arms 71a extending between the two sets of links about to be described. The lower links 72 are pivotally mounted at 73 to crosshead 64 in the form shown there being a pair of parallel elements for each link, it being apparent that single elements could be used. There are four sets of links, one set being pivotally connected at point 73 to each corner of the crosshead 64. The lower links 72 are pivoted at their upper ends to the lower ends of the upper links 74 at pivots 76, said pivots 76 being carried by the link operating connectors 74 and 71a. The upper ends of the upper links are pivotally mounted at 75 to the mill frame, a shaft extending between said pivot points if desired.

When the piston is in its extreme left position (Fig. 2) crosshead 64 will be in its uppermost position so that springs 61 will maintain rods 63 in their uppermost position, thus holding the upper roll guide bearings 16 and 17 and the upper roll in an uppermost position. The upward movement of rods 63 is limited by collars 62 contacting the uppermost position of the bores 92, or by the bushings 77 contacting their respective cover plates 66.

When it is desired to remove the upper roll, keeper plates 26 first are loosened and then the hydraulic cylinder 67 energized so as to move the piston rod 70 to the right (Fig. 2), pipes 93 and 94 being provided for the supply and exhaust of fluid operating medium for the hydraulic cylinder 67 in a well known manner. Upon movement of the piston rod 70 to the right, the pivot points 76 will straighten out relative to each other so as to move the crosshead 64 downwardly, thus causing rods 63 to move downwardly therewith. The links 72 and 74 may be operated as a toggle joint by bringing the common pivots 76 to the right (Fig. 2) of a straight line joining link pivot points 73 and 75, thus automatically locking rods 63 in a downward position.

Downward movement of the crosshead 64 will permit the upper roll, the carrier bearings, the roll chocks, and carrier 21 to move downwardly away from the housing screws 30 and 31 so that the entire upper roll assembly can be lifted or moved horizontally relative to the upper ends of rods 63 (Fig. 1) and through the windows of the roll housing.

After completion of the removal of the upper carrier as a unit, the lower carrier can be moved upwardly in the windows 22 upon release of locking pins 51, and then the lower carrier, the lower roll, the lower roll chocks, and lower roll guide bearings moved horizontally as a unit out of the roll housing between the windows thereof.

It also would be possible to remove the lower carrier assembly after the upper assembly has been removed by sliding the flanged collar 45

outwardly on stud 43 with the carrier, instead of lifting the roll carrier frame thereover.

Any type of conventional driving connections 95 may be employed to connect the rolls with suitable driving apparatus therefor as is well known in the art.

A modified form of the invention is shown in Figs. 5 to 8, inclusive, wherein the roll carrier frames have a slightly different form, and an adjusting means for the height of the lower roll 10 relative to the mill housings is provided. A detailed description of the screw-downs and operating mechanism therefor together with the elevating and lowering mechanism for the upper roll bearing carriers is omitted because these are substantially the same as described for Figs. 1 to 4, inclusive.

Roll carrier frame 78 has flanges 79 extending either side thereof for engagement with the uprights 81 of roll housing 82, said flanges having a greater width than the window 80 between said uprights of housing 82. Bolts or studs 83 pass through uprights 81 and are held in place by nuts 99. Bushings 98 of varying lengths may be employed to suitably position horizontally the flanges 79 relative to uprights 81 and thereby position the roll carrier frame relative to the mill housings. Studs 83 pass through elongated slots 84 in flanges 79 so as to allow vertical movement and adjustment of the roll carrier frame relative to roll housing 82 and nuts 83a hold the carrier in adjusted position.

The upper roll chock 96 may be fastened to roll carrier frame 78 by means of bolts 97. The upper roll chock 85 is positioned longitudinally relative to the upper roll 86 by means of adjusting screws 87, said roll chock exerting a pressure against the thrust bearings of the roll chock in a manner similar to that described for Figs. 1 to 4, inclusive. The roll guide bearings 100 and 101 can be supported by means of rods 102 similar to that described for Figs. 1 to 4, inclusive.

Lower roll 103 is supported in lower roll chocks 104 and 105, roll chock 105 being fastened by screws 106 to the lower roll carrier frame 107. Roll chock 104 is positioned longitudinally relative to roll carrier frame 107 by means of adjusting bolts 108. Flanges 109 of the roll carrier frame 107 may have elongated slots 110 through which pass the holding studs 111 similar to that for the upper carrier with the exception that an adjustable nut 112 can be provided for adjusting the position of the carrier longitudinally relative to the housing uprights 81. The lower roll carrier frame 107 is supported on saddles 114 carried in seats 115, seats 115 having sloping lower faces slidably relative to the movable wedges 116. Wedges 116 have nuts 117 engageable with the oppositely threaded screws 118. By turning screws 118, wedges 116 are moved inwardly and outwardly relative to each other so that the height of the lower roll carrier frame 107 relative to the mill housing can be adjusted thereby.

The roll carrier frames and assemblies of the modification shown in Figs. 5 to 8, inclusive, can be removed as units and adjusted, or the parts replaced, or new assemblies placed in the housing, in a manner similar to that described for Figs. 1 to 4, inclusive.

Still another modification of the form shown in Figs. 5 to 8, inclusive, can be seen in Figs. 9 and 10, it being understood that the modification of Figs. 9 and 10 also could be applied to the form shown in Figs. 1 to 4, inclusive. Uprights 119 of roll housing 120 form windows 121 in which the

upper roll carrier frame 122 and lower roll carrier frame 123 are mounted in a manner similar to that just described for the modification of Figs. 5 to 8, the upper roll being shown at 124 and lower roll at 125. The upper roll guide bearings 126 and the lower roll guide bearings 127 have a plurality of bolts or connectors 128 loosely passing through the flanges of said roll guide bearings on both sides of the bearings. Springs 129 surrounding bolts 128 serve to keep the roll guide bearings separated relative to each other. One or any number of bolts may be employed for each pair of flanges as desired. The arrangement of Figs. 9 and 10 takes the place of the rods holding up the lower roll guide bearings of the previously described modifications. The springs will urge the guide bearing halves apart and thus the rolls will be urged apart so that the roll necks of each roll will be urged against its chock.

The two-piece roll chocks and roll guide bearings can be replaced by roller bearings, such as shown in Fig. 11. Upper roll 130 can have roller bearing assemblies 131 and 132 mounted in the upper roll carrier frame 133, the bearing cage or enclosure of bearing 132 being fastened to said carrier frame by means of bolts 134. The roller bearing 131 can be positioned longitudinally relative to the carrier frame by means of adjustable bolts 135. The lower roll 136 has roller bearings 137 and 138 supported in the lower carrier yoke 139 in a manner generally similar to the upper roll. The roll assembly in its carrier frame in this form can be removed from the roll housing as a unit and adjusted or replaced outside of the roll stand, as desired, in a manner similar to that described for the other modifications of the invention. The upper set of roller bearings may be supported on rods (not shown) similar to the rods 63 and 102 of the previously described forms.

Several illustrative embodiments have been described and illustrated herein, and it is apparent that various modifications and departures can be made in the details thereof without departing from the spirit of the invention except as defined in the appended claims.

I claim:

1. In a horizontal rolling mill having a pair of roll housings, the combination comprising an upper roll assembly carrier frame, roll bearing elements longitudinally adjustably mounted in said carrier frame, an upper roll carried by said bearing elements, adjustable bearing positioning elements engageable with said bearing elements and frame for adjustably positively locating said bearing elements and roll horizontally relative to its carrier frame, carrier frame securing means engageable with one of said housings and said carrier frame detachably connecting said roll assembly carrier frame to one of said housings, and a releasable normally elevated bearing supporting mechanism engaging at least some of said bearing elements and vertically holding the same, whereby said carrier frame with the bearing elements and rolls assembled thereto can be readily inserted and removed as a unit from the roll housings.

2. In a rolling mill having a pair of roll housings and a main frame, the combination comprising an upper roll assembly carrier frame, roll bearing elements longitudinally adjustably mounted in said carrier frame, an upper roll carried by said bearing elements, adjustable bearing positioning elements engageable with said

bearing elements and frame adjustably locating said bearing elements and roll relative to its carrier frame, carrier frame securing means engageable with one of said housings and said carrier frame for detachably connecting said roll assembly carrier frame to said housing, spring supported upwardly urged rods engaging at least some of said bearing elements normally holding said carrier frame in a vertical position, normally inactive toggle links connected to said rods and with said main frame, and toggle link activating mechanism connected to said toggle links to move said links and lower said rods against spring pressure, whereby said carrier frame with the bearing elements and rolls assembled thereto can be readily inserted and removed as a unit from the mill housings.
